UNITED STATES PATENT OFFICE

JOSEPH MUROS, OF ASTORIA, NEW YORK, ASSIGNOR TO GILLETTE SAFETY RAZOR COMPANY, OF BOSTON, MASSACHUSETTS, A CORPORATION OF DELAWARE

SAFETY RAZOR

Application filed April 10, 1931. Serial No. 529,155.

This invention relates to safety razors of the type in which a thin flexible blade is positioned for shaving purposes in a holder having relatively movable clamping members. It is desirable for the convenience of the user that in assembling the razor for shaving and in disassembling it for cleaning purposes after shaving the blade clamping parts should be quickly and reliably moved to and from the blade clamping position. Further, that in the open position of the holder the blade may be conveniently presented for removal or replacement without danger of cutting the user or of being improperly positioned in the clamping operation.

In one aspect the present invention consists in a holder having blade clamping parts arranged for movement toward and from each other, and also transversely with respect to each other, so that when the blade clamping pressure is released one of the blade clamping parts may be moved completely to expose the blade. With the clamping parts so disposed the user may remove or replace the blade conveniently and without loss of time. Moreover, by constructing the parts so that their clamping movement is properly controlled, the correct position and edge exposure of the blade are insured for the shaving operation.

As herein shown, I secure the desired results by providing both the guard and the cap members of the holder with handle portions which are so related and connected as to insure the desired movement of the parts. The handle part of one member is guided for longitudinal movement within the handle part of the other member and means are provided whereby a transverse movement of the two members is permitted when they have reached a predetermined amount of separation such that the blade may be freely exposed by an ensuing transverse movement of the two.

In accordance with a preferred feature of the invention I may provide a single operating device for controlling both the movement of separation of the blade clamping members and their transverse movement to expose the blade. As herein shown, this comprises

an arm or lever having a toggle connection with the handle part of the guard member and so designed that the final clamping movement of the cap and guard is effected by powerful toggle action insuring firm engagement of the blade under adequate pressure to hold the same and if desired to impart to it a pronounced transverse curvature. This mechanism as herein shown is also utilized to control the transverse movement of the cap and guard so that by single movement of the operating device the cap and guard are first separated and then transversely displaced in opening the razor, or first positioned in an alignment and then moved into clamping engagement in closing the razor preparatory to shaving.

These and other features of the invention will best be understood and appreciated from the following description of a preferred embodiment thereof selected for illustration and shown in the accompanying drawings in which,

Fig. 1 is a view of the complete razor in side elevation.

Fig. 2 is a fragmentary view in longitudinal section on line 2—2 in Fig. 5.

Fig. 3 is a view in transverse section on the line 3—3 of Fig. 2.

Fig. 4 is a view of the razor in longitudinal section on line 4—4 in Fig. 5, showing the razor in opened condition.

Fig. 5 is a view of the razor in longitudinal section on line 5—5 in Fig. 1.

Fig. 6 is a fragmentary view, partly in section, showing the parts of the razor in an intermediate position, and

Fig. 7 is a plan view of the razor in open condition.

The razor herein shown comprises a cap member 10, shown having a concave blade shaping face, and a guard member 12, shown having parallel fulcrum shoulders over which may be bent a flexible blade 14 when the cap and guard occupy blade clamping position, as shown in Fig. 1.

The cap 10 is supported at each end by the arms 20 of a yoke shaped member in a spaced relation to and about its handle part 22 which is formed as an open-sided channel substan-

tially rectangular in internal contour. The cap is shown provided at each corner with a reinforcing lug 18 and with a pair of aligned blade locating ribs 16 which are spaced from each other as shown in Fig. 5. Between these ribs the cap is provided with a recess 9 designed to receive with appreciable clearance the blade-positioning rib 13 of the guard.

10 The guard member 12 is shown detachably secured to the upper end of its handle part which comprises a rectangular stem or bar 24 of the proper shape and dimensions to slide within the channel of the handle part 22 and be guided telescopically thereby. The guard member is provided with a central longitudinal groove 11 to receive the ribs 16 of the cap and with a centrally disposed projecting rib 13 shaped to fit the central aperture of the blade 14.

15 It will be understood that the handle part 22 of the cap and the stem 24 of the guard are assembled in telescopic relation, the stem sliding longitudinally within the channel of the handle and being guided thereby so that the guard 12 may be moved to free the cap 10 in a direction substantially normal to its curved blade shaping face.

20 Means will now be described for controlling the relative movement of the two principal razor parts above described. A finger lever or member 28 is pivotally mounted in the lower end of the handle part 22 to swing about a transverse pin 26 which extends between the opposite walls thereof. The handle 22 is notched in its face at 22' to receive the finger lever 28 when the lever occupies a vertical position as shown in Figs. 1 and 2, in which position its outer surface is flush with the surface of the handle. The handle 22 is provided also at its lower end with a flange which substantially closes the bottom end of the channel in the handle when the finger lever is in its 25 closed position. The finger lever is pivotally connected at an intermediate point to the stem 24 by means of a link 30 and acts through this link to operate the stem 24. Link 30 is shown pivotally connected at 30' and 30" with the stem 24 and lever 28. It will be observed from inspection of Figs. 4 and 6 that the link 30 and the lower or inner portion of the finger lever 28 act as a toggle in operating the stem 24. The toggle is 35 straightened by the lever action of the finger lever 28 so that a powerful clamping action between the cap and guard is secured with slight effort on the part of the user when the lever 28 is swung against the handle part 22.

40 The longitudinal or vertical movement of the guard member has been discussed hitherto. This is utilized in effecting the preliminary separating movement between the cap and the guard and their final 45 movement into clamping engagement with

the blade. As herein shown, however, the guard member is arranged to swing transversely out from beneath the cap after it has been separated from the latter by a predetermined amount. To this end the stem 24 is provided with the transverse guide pin 32 which is located at a point somewhat above the bottom of the stem. The guide pin 32 extends beyond the stem on both sides and slides in vertical slots or grooves 23 formed in opposite sides of the channel walls of the handle 22. The path of movement of the pin 32 in that portion of the channel is consequently positively controlled at all times. When the stem 24 is elevated in the handle 22 its inner face bears against the rear wall of the channel of the handle both above and below the guide pin 32 and under these circumstances no transverse movement of the stem is possible at either end. The rear wall of the channel member is provided near its lower end with a recess 21 which will permit that portion of the stem 24 below the guide pin 32 to enter it when the stem is lowered into registration with it as shown in Figs. 4 and 6. The link 30 is provided with a notch or recess to receive the guide pin 32 when the finger lever is swung into its upright position, as best shown in Fig. 2.

50 The operation of the razor construction above described will be apparent but for convenience may be summarized as follows. With the parts in the position shown in Figs. 4 and 7 the user may conveniently place the blade 14 upon the exposed face of the guard 12, and the blade will be properly and accurately positioned thereon by the engagement of the rib 13 of the guard in the blade locating aperture 14' of the blade. By swinging the finger lever 28 upwardly the stem 24 is 55 rocked in an anti-clockwise direction as seen in Fig. 4 about the guide pin 32 as a fulcrum until it reaches a position in the handle part 22 in vertical alignment with and beneath the cap 10. In this movement the lower end of the stem 24 is moved out of the recess 21 so that the stem is now free to move vertically. The parts are shown in this position in Fig. 6. Continued movement of the finger lever 28 in the same direction thereupon is effective bodily to elevate the stem 24, and the guard, carrying the guide pin 32 upwardly in the slots 23 and clamping the blade 14 between the guard and the cap. In this movement the ribs 16 of the cap enter the groove 11 in the face of the guard and the rib 13 enters the recess 9 in the cap and thus the two members are positively centered with respect to each other and are retained from transverse movement relatively one to the other.

60 After the shaving operation, or when the user wishes to replace a blade, the sequence of operation above set forth is reversed. In the initial outward movement of the finger lever 28 the stem 24 is moved vertically down-

ward until the blade is entirely separated from the cap and until the end of the stem 24 is brought into registration with recess 21. Thereupon the further final movement of the 5 finger lever swings the stem 21 and the guard outwardly carrying the blade into the exposed position, the inner lower end of the steam 24 engaging the handle part 22, and limiting the outward movement of the guard 10 member, as illustrated in Fig. 7.

The screw-threaded connection of the guard 12 with its stem 24 affords provision for adjustment so that when the finger lever is moved fully to its closed position as shown 15 in Figs. 1 and 2 the proper degree of clamping blade pressure is exerted by the cap and guard.

Having thus described my invention, what I claim as new and desire to secure by Letters Patent is,—

1. A safety razor having cap and guard members arranged to clamp a flexible blade between them, said members having telescopically connected handle parts construct- 25 ed and arranged for relative longitudinal movement, and one of said parts having clearance at a predetermined point to permit angular movement of the other only in one position of separation, and manually operated 30 means for effecting both longitudinal and angular movements of said part.

2. A safety razor having blade-clamping members provided respectively with handle parts having a common pivotal connection ar- 35 ranged to be shifted longitudinally in one part, a finger lever pivotally mounted in said part, and a link interposed between said lever and the other part and arranged first to swing said other part and then to move it longitudinally in clamping a blade for shaving.

3. A safety razor having blade clamping members provided respectively with handle parts, one of said parts having a channel provided with an open side, the other of said 45 parts being adapted to slide longitudinally within and move laterally into and from said channel, means pivotally and slidably connecting said handle parts, said handle parts being adapted to engage in one position there- 50 of to prevent lateral movement of said parts relatively one to another, and means to permit said parts to move laterally relatively one to another with respect to the open side 55 of the channel when they are in a different position.

4. A safety razor as set forth in claim 3 in which the means for pivotally and slidably connecting parts include a pin connected with 60 one of the parts, the other part having longitudinally extending grooves receiving said pin.

5. A safety razor as set forth in claim 3 provided with a finger lever connected with 65 one of said parts and a link connecting the

finger lever with the other of said parts for causing relative movement of said parts.

6. A safety razor comprising a guard member provided with a handle part, a cap provided with a handle part, one of said parts having a channel open on one side and adapted to receive the other part, and means slidably and pivotally connecting said handle parts to permit the latter to move longitudinally relatively one to the other and to 75 swing laterally with respect one to another, said parts in blade-clamping position engaging one another to prevent lateral displacement of the guard member from the cap 80 while in such position.

7. A safety razor as set forth in claim 6 in which one of the handle parts is provided with a recess to receive an adjacent portion of the other part to permit lateral movement 85 of the last-named part relative to the first-named part when the guard member has been moved appropriately from the shaving position.

8. A safety razor having blade-clamping members each provided with a handle part, 90 a common pivotal connection between said handle parts arranged to be shifted longitudinally thereof, a finger lever mounted in one of said parts, a link interposed between said lever and other part and arranged first to 95 swing said other part and then to move it longitudinally in clamping a blade for shaving, and means for adjustably connecting one of said blade clamping members to its handle part.
